RELEASEABLE APPARATUS FOR RETRIEVING SUBSURFACE WELL DEVICES

Reuben C. Baker, Coalinga, and Martin B. Conrad,
Downey, Calif., assignors to Baker Oil Tools, Inc., Los
Angeles, Calif., a corporation of California

Application October 12, 1953, Serial No. 385,335

17 Claims. (Cl. 166—125)

The present invention relates to subsurface well bore apparatus, and more particularly to apparatus useful in retrieving a device from a well bore.

An object of the present invention is to provide an improved retrieving apparatus adapted to be coupled to a well device in a well bore for the purpose of moving the device to another well bore location, or to completely remove it from the well bore, the apparatus being releasable from the well device at any time at the will of the operator.

Another object of the invention is to provide an improved retrieving apparatus of the character indicated which is capable of effecting lowering of the well device in a well bore, as well as its elevation therewithin.

A further object of the invention is to provide an improved retrieving apparatus capable of being coupled automatically to a well bore device when lowered in the well bore and which is releasable hydraulically from the well device.

Still another object of the invention is to provide a retrieving apparatus capable of being coupled automatically to a well bore device when lowered in the well bore and which is positively locked to the device in response to an upward pull taken on the apparatus, to preclude inadvertent release of the apparatus from the well device.

Yet a further object of the invention is to provide the combination of a well bore device and a retrieving apparatus for lowering and elevating the device in a well bore, in which the apparatus may be coupled to the device at the will of the operator, and which apparatus can also be released from the device at any time at the will of the operator. The coupling and release of the device can be effected repeatedly while the combination is in the well bore, if desired.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figures 1 and 1a together constitute a longitudinal section of apparatus embodying the invention, with the parts positioned for lowering the apparatus in a well casing, or similar conduit, Fig. 1a constituting a lower continuation of Fig. 1;

Figs. 2 and 2a are views similar to Figs. 1 and 1a, disclosing the retrieving apparatus of the combination illustrated released from the well device therebelow;

Fig. 3 is a partial longitudinal section similar to Fig. 2a disclosing a particular well device to which the retrieving apparatus can be coupled, with its parts occupying another position in the well casing;

Figs. 4 and 4a are views similar to Figs. 1 and 1a, illus-

trating the retrieving apparatus coupled to the well device therebelow;

Fig. 5 is a cross-section taken along the line 5—5 on Fig. 4;

Fig. 6 is a cross-section taken along the line 6—6 on Fig. 1a;

Fig. 7 is an enlarged partial longitudinal section of the retrieving device coupled to the well device therebelow, the parts occupying the position disclosed in Fig. 4.

10 The retrievable well packer or bridge plug A is adapted to be connected to a running-in and retrieving tool B, which, in turn, is connected to the lower end of a tubular string of drill pipe or tubing C, or to the lower end of another well tool (not shown), such as an upper retrievable packer adapted to be anchored to the well casing. The well packer A is run in the well casing D to the desired setting point, after which the retrieving tool B is disconnected therefrom and elevated from the well packer or plug A. The latter is then capable of being 15 anchored in leakproof relation against the well casing to preclude longitudinal movement of the plug in both directions. Thereafter, if it is desired to release the tool A from the well casing and to remove it, the retrieving tool B is again connected to the bridging plug A, and the latter then moved longitudinally in the well casing in either an upward or a downward direction. During movement of the bridge plug in either longitudinal direction in the well casing, fluid is allowed to by-pass through the packer. However, following the release of the retrieving tool B from the packer, the by-pass passage is 20 automatically closed.

25 As disclosed in the drawings, the bridge plug or well packer portion A of the apparatus includes a central coaxially disposed body 10 which, for purposes of convenience of manufacture and assembly of the apparatus, is made into several portions, including an upper body portion 11, the lower end of which is threaded onto the upper end of a lower body portion 12. A set of upper segmental slips 13 is disposed around the packer body, these slips having upper head portions 14 whose inner surfaces 15 are inclined in a downward and inward direction for cooperation with companion tapered surfaces 16 on an upper expander 17 that is suitably secured to the body 10 of the tool. When the upper expander 17 is moved downwardly with the body 10 relative to the upper slips 13, the latter are urged in an outward direction to embed their wickers 18 into the wall of the well casing or conduit D, thereby anchoring the body 10 of the tool to the conduit against downward movement.

30 The upper expander 17 is prevented from moving longitudinally of the body 10 by having its lower smaller end engage a shoulder 19 on the body, with its upper end bearing against a packing cup thimble 20 which receives the lower or base portion 21 of an upwardly facing packing cup 22, which may be made of rubber or rubber-like material. This cup has an upper lip portion 23 adapted to slidably seal against the wall of the well casing D, to prevent downward passage of fluid between the packing cup and the casing wall. Fluid is prevented from 35 passing between the base portion 21 of the packing cup and the packer body 10 by a side seal ring 24 of rubber or rubber-like material in a groove 25 in the body adapted to bear against a metallic sleeve 26 secured in the base portion 21 of the packing cup. The packing member 22 itself is prevented from moving longitudinally with respect to the body 10 by a clamp and valve cage device 27, the lower portion of which is threaded onto the upper end of the body 10 and bears against the base 21 of the packing cup, the latter, in turn, bearing against the thimble 20, which engages the upper expander 17 that, as previously described, has its lower portion engaging the body shoulder 19.

A set of lower segmental slips 28 also encompasses the body 10, these lower slips including lower head portions 29 whose inner surfaces 30 taper in an upward and inward direction for cooperation with companion tapered surfaces 31 on a lower expander 32 that is secured to the body of the tool. The lower expander is prevented from moving longitudinally of the body by having its upper small end engage a shoulder 33 provided by the lower end of the upper body portion 11, and with its lower end engaging a lower thimble 34 surrounding the body and receiving the base portion 35 of a lower packing member 36, which is similar to the upper packing member 22, although reversed in position on the body 10 of the tool. This base portion 35 also carries a sleeve 37 adapted to seal against a rubber or rubber-like seal ring 38 carried in a ring groove 39 in the periphery of the body, to prevent fluid leakage between the packing and the body. The packing 36 faces in a downward direction and has its lower lip portion 40 adapted to slidably seal against the wall of the well casing D, to prevent upward passage of fluid between the packing and the well casing. In a manner similar to the upper packing 22, the lower packing device is prevented from moving longitudinally on the body 10 by a lower retainer and valve cage 41 threaded onto the lowermost portion of the lower body member 12 and bearing against the base 35 of the packing, clamping the latter against its thimble 34, which, in turn, engages the lower end of the lower expander 32 that is prevented from moving upwardly by the body shoulder 33. If desired, the expander 32 may be further secured to the body 10 by one or more screws 42.

When the body 10 of the tool and the lower expander 32 move upwardly with respect to the lower set of slips 28, the lower expander will shift the lower slips laterally outward, to embed their wickers 43 into anchoring engagement in the wall of the well casing D, thereby preventing the tool from being moved upwardly within the well casing. The lower packing 36 will prevent fluid from passing in an upward direction between the body 10 of the tool and the well casing D.

Relative longitudinal movement between the body 10 and the expanders 17, 32 mounted thereon, on the one hand, and the sets of upper and lower slips 13, 28, on the other hand, is secured by resisting the longitudinal movement of the slips through the provision of a drag device. This drag device includes longitudinally extending drag blocks 44 circumferentially spaced from one another and slidably mounted in longitudinal grooves 45 in a slip and drag block housing 46 slidably along the periphery of the body 10 of the tool. The drag blocks 44 are urged outwardly into frictional engagement with the wall of the well casing D by a plurality of helical compression springs 47 received within internal sockets 48 in each drag block and bearing against the bases of the sockets 48 and also against the bases 49 of the confining housing grooves 45. Outward movement of the drag blocks 44 is limited by the engagement of their upper and lower terminal portions 50 with upper and lower stop rings 51 secured to the housing in any suitable manner, as through use of the screws 52 attaching the rings to the housing 46.

Both the upper and lower sets of slips 13, 28 are secured to the housing 46, in order that the drag blocks 44 will resist their movement within the well casing, and enable the body 10 and the upper and lower expanders 17, 32 to be shifted longitudinally with respect thereto. Thus, the upper slips 13 have depending arms 53 terminating in inwardly directed flanges 54 received within a circumferential groove 55 provided in the midportion of the housing 46 between the circumferentially spaced drag blocks 44. Each slip segment structure is provided with a plurality of spaced longitudinally extending slots extending throughout substantially its entire length to a region adjacent the flange 54, so that the

arms 53 are flexible and will allow the slips to be deflected in an outward direction into engagement with the wall of the well casing D. The flange portions 54 of the slips themselves are prevented from coming out of their companion groove by an arcuate holding device 57 disposed across the flange portion 54 and secured to the slip and drag block housing 46 by one or more screws 58.

The lower set of slips 28 is attached to the housing 46 in the same manner as the upper set of slips 13, this lower set of slips having upper inwardly directed flanges 54 received within arcuately spaced grooves 55 in the housing between the drag blocks 44, and retained therein by the same slip holder 57 that maintains the upper slip flanges 54 in their grooves. The lower slips 28 are also provided with longitudinal slots from a region adjacent their flange portion 54 to the lower end of the slips, to provide the flexible or spring-like arm 53a that will enable the head portion 29 of the slips to be expanded laterally outward into anchoring engagement with the well casing D.

The drag block stop rings 51 are spaced laterally outward away from the slip arms 53, 53a a sufficient distance to allow the heads 14, 29 of the slips 13, 28 to move without restraint laterally into engagement with the well casing. The slips themselves normally tend to remain in an inward direction because of the spring characteristics of the arm portions 53, 53a. However, assurance is had that the slips are held in a retracted position when they are not to be expanded outwardly into engagement with the well casing by providing slip retainer and retractor rings 60, 61 for the upper and lower sets of slips 13, 28. Thus, a ring 60 can be disposed around the shoulder portions 62 of the upper set of slips 13 which interconnect the head and arm portions 13, 53, the shoulder portions being thicker in radial dimension than the arm portions, their outer surfaces being adapted to engage the ring 60, which will prevent the wickers 18 of the head 14 from moving into engagement with the casing wall. The shoulder portions 62 are interconnected with the arm portions 53 by the tapered surfaces 63, which are capable of engaging the upper end of the ring 60 in order to urge the slip heads 14 in an inward direction.

The retainer and retractor ring 60 is supported in position by a plurality of longitudinally extending bars 64 disposed between the slip segments 13, their lower ends being welded to the upper end of the ring 60 and their upper portions being clamped between the upper expander 17 and upper thimble 20, the upper portions of the bars being prevented from disconnecting from the upper expander by a holding ring 65 encompassing the bars and suitably secured to the expander, as by one or more screws 66.

The lower set of slips 28 is similarly held in its retracted position against inadvertent outward movement by a lower retainer and retractor ring 61 encompassing the enlarged shoulder portions 67 of the lower slip, the lower end of this ring being engageable with the tapered surfaces 68 on the slip segments interconnecting the shoulders 67 and the arm portions 53a, to urge the lower slip heads 29 inwardly away from engagement with the casing, in the manner described hereinbelow. The lower ring 61 is held in appropriate position by a plurality of circumferentially spaced and longitudinally extending bars 69 welded, or otherwise suitably secured, to the lower end of the ring 61, the bars being clamped between the lower expander 32 and the lower thimble 34, being held in appropriate position on the lower expander by an encompassing holding ring 70 secured to the lower expander by one or more screws 71. As is true of the upper sets of slips 13, the lower stop ring 51 is spaced sufficiently away from the lower slip arms 53a to avoid interference with the lateral outward movement of the lower slips 28 into engagement with the well casing D.

Since the drag blocks 44 are resisting longitudinal movement of the upper and lower sets of slips 13, 28 in the well casing, relative longitudinal movement of the body 10 and the upper and lower expanders 17, 32 connected thereto will expand either the upper or the lower slips into anchoring engagement with the wall of the well casing, depending upon the direction of longitudinal movement of the body 10 and the expanders 17, 32. Thus, should the body and the expanders be moved downwardly, then the upper expander 17 will be moved down within the upper slips 13, shifting the latter radially outward into anchoring engagement with the well casing, these slips, in effect, bending or rocking about their lower flange portion 54. It is to be noted that when the upper slip heads 14 are in their retracted position, the tapered slip surfaces 15 are not parallel to the expander surface 16 but make an acute angle with respect thereto. The difference in inclination is provided so that when the slips 13 are rocked outwardly into engagement with the well casing the surfaces 15, 16 are substantially parallel, enabling the expander surface 16 to make full bearing engagement against the slip surfaces 15, as is evident from an inspection of Fig. 2a.

The relative downward movement of the body 10 and expanders 17, 32 with respect to the slips will anchor the upper slips 13 against the well casing. However, the lower slips 28 will still remain in a retracted position, since the lower expander 32 is merely moved downwardly away from the lower slips. On the other hand, should the body 10 be moved in an upward direction, then the body and expanders 17, 32 will be shifted upwardly with respect to the slips, the upper expander 17 moving out of wedging engagement within the upper slips 13, this upward movement causing the retractor ring 60 to engage the tapered slip surface 63, to insure the inward movement of the slip heads 14 out of engagement with the well casing, the ring 60 moving at least slightly over the shoulder portion 62 to retain the slips 13 in this retracted position.

The upward movement of the lower expander 32 will move the lower retainer and retractor ring 61 out of a position to engage the lower slip shoulders 67, whereupon the lower expander 32 can be wedged upwardly within the lower slips 28 to urge the latter radially outward into engagement with the wall of the well casing. As is true of the upper expander 17 and upper slips 13, the tapered surfaces 31, 30 on the lower expander 32 and lower slips 28 are not parallel to one another when the lower slips are in retracted position, the surfaces making an acute angle with respect to each other. But when the lower expander 32 moves upwardly within the lower slips 28, the latter are rocked or pivoted about their flange portions 54 outwardly against the casing D, in which position their tapered surfaces 30 will be substantially parallel to the lower expander tapered surface 31 to insure full bearing engagement between the expander 32 and slips 28.

It is, therefore, apparent that when the body 10 and expanders 17, 32 are moved in a downward direction that the upper slip retainer 60 is moved out of its holding position with respect to the upper slips 13, but the lower slip retainer 61 remains in its holding position with respect to the shoulders 67 of the lower slips 28, the upper expander 17 then shifting the slips 13 outwardly into anchoring engagement with the wall of the well casing. Conversely, upon upward movement of the body 10 and the expanders 17, 32 the upper retractor ring 60 moves in a position to urge and hold the upper slip heads 14 in a retracted position, the lower retainer ring 61 being shifted upwardly by the lower expander out of holding engagement with the lower slips 28, whereupon the lower expander 32 can be wedged upwardly within the lower slip heads 29, to urge them laterally outward into anchoring engagement with the wall of the well casing D.

The ability of either the upper or the lower sets of slips to be moved in a lateral outward direction depends upon

the relative longitudinal movement of the body and expanders with respect to the slips. Such relative longitudinal movement is prevented until it is desired to secure an anchoring of the packer or plug in the well casing. As disclosed in the drawings, the slip and drag block housing 46 is provided with a pair of diametrically opposed longitudinal slots 73 in its inner wall in which the outer ends of a flat cross-piece or bar 74 are received, such outer ends of this bar being adapted to engage the lower ends 73a of the slots or the upper ends 73b of the slots. This cross-piece 74 extends through diametrically opposite longitudinal slots 75 in the body in alignment with the housing slots 73, but having a greater length than the housing slots.

The cross-piece 74 also extends through a transverse slot 76 in a control rod 77 extending completely through the packer body 10. This control rod has an upper reduced diameter portion 78 slideable through the transverse portion 79 of the upper valve cage 27. It also has a lower reduced diameter portion 80 slideable through the lower transverse portion 81 of the lower valve cage 41. Thus, the valve cages 27, 41 retain the control rod 77 coaxially of the body 10 of the tool, while permitting the rod 77 to slide longitudinally in an upward or downward direction relative to the body 10 of the tool. The main intermediate portion of the control rod 77, through which the cross-piece 74 extends, has a diameter substantially less than the inside diameter of the body 10, to afford ample passage area for the flow of fluid through the body, as described hereinbelow.

When the control rod 77 is shifted downward with respect to the body, the cross-piece 74 will engage the lower ends 73a of the housing slots 73 and will shift the housing 46 in a downward direction along the body 10 a comparatively short distance, until the cross-piece engages the lower ends 73a of the body slots. The distance that the slip and drag block housing 46 is thus moved in a downward direction along the body 10 is comparatively short, the parts being so proportioned that the drag block housing 46 and the slips 13, 28 connected thereto are disposed in substantially a central position between the upper and lower expanders 17, 32. Thus, with the cross-piece 74 engaging the lower ends 73a, 73a of the body slots 75 and the housing slots 73, downward movement of the control rod 77 will carry the body 10 and the drag block housing 46 downward as a unit, so that there is no relative downward movement of the upper and lower expanders 17, 32 with respect to the upper and lower slips 13, 28, the latter remaining in their neutral position, such as disclosed in Fig. 1a. Similarly, in the event the control rod 77 is moved upwardly within the body, the upper ends of the cross-piece 74 will engage the upper ends 73b, 73b of the body slots 75 and the housing slots 73, further upward movement of the control rod then carrying the body 10 and housing 46 upwardly as a unit with it, the body being prevented from moving upwardly relative to the housing 46, which would result (if it could occur) in upward movement of the lower expander 32 within the lower slips 28 and anchoring engagement of the latter with the wall of the well casing.

When the cross-piece 74 is placed in an intermediate position within the housing and body slots 73, 75, then the body 10, and the upper and lower expanders 17, 32 connected thereto, can move selectively in an upward or a downward direction with respect to the housing 46 and the upper and lower slips 13, 28 connected thereto. When there is no upward or downward directed force imposed on the control rod 77 tending to shift its cross-piece 74 either down within the body and housing slots 75, 73 or upward therewithin, the control rod 77 and its cross-piece are disposed in a central position with respect to the slots, such as disclosed in Figs. 2a and 3. Such central disposition is provided by upper and lower springs 85, 86. The springs not only are utilized to locate the control rod 77 in a central position, but they are also availed of to

determine the open or closed position of the passage 87 through the packer or bridge plug body.

The upper helical compression spring 85 is disposed on the upper reduced diameter portion 78 of the control rod, this spring engaging the upper valve cage 27 and also an upper valve head 88 which is slideable in a downward direction along the reduced diameter portion 78 of the control rod into engagement with a valve seat 89 provided within the upper portion of the tool body 10. Thus, the spring 85 tends to urge the valve head 88 downwardly, so that its cylindrical portion 88a is disposed within the upper valve seat 89, as determined by engagement of the valve head stop flange 90 with the upper end 91 of the body 10. The valve head 88 is provided with a suitable rubber or rubber-like side seal ring 92 in a peripheral ring groove 93 engageable with the cylindrical valve seat portion 89 of the body of the tool. Leakage of fluid between the control rod 78 and the valve head 88 is prevented by a rod packing ring 94 disposed in an internal groove 95 in the valve head and engaging the periphery of the rod 78.

A lower valve device is also provided, including a lower valve head 96 urged in an upward direction into sealing engagement with a cylindrical valve seat 97 provided at the lower end of the packer body 10. The helical compression spring 86 surrounds the lower reduced diameter portion 80 of the control rod, its lower end bearing against the lower transverse portion 81 of the valve cage 41 and its upper end against the valve head 96, urging the latter in an upward direction to shift it within the lower cylindrical valve seat 97, as determined by engagement of a flange 98 on the valve head with the lower end 99 of the body 10. Leakage of fluid between the head 96 and the cylindrical valve seat 97 is prevented by a side seal ring 100 mounted in a peripheral groove 101 in the valve head and adapted to sealingly engage the valve seat 97. Leakage of fluid between the lower reduced diameter rod portion 80 and the lower valve head 96 is prevented by providing a rod packing ring 102 in an internal groove 103 in the valve head slidably and sealingly engaging the control rod 80.

The upper valve head 88 can be urged downwardly by the upper spring 85, not only to shift the upper valve head into sealing engagement with the upper valve seat 89, but also to engage the valve head 88 with an upper shoulder 104 formed on the control rod between its upper 78 and central portions, and tending to shift the control rod 77 in a downward direction. Similarly, the lower spring 86 urges the lower valve 96 in an upward direction toward a position of engagement with its valve seat 97, this lower valve head being adapted to engage a lower downwardly directed shoulder 105 formed between the intermediate portion of the rod 77 and its lower reduced diameter portion 80, tending to elevate the rod 77 within the packer body 10. When the rod 77 is unrestrained by external forces, the springs 85, 86 will shift the valve heads into engagement with their seats, the heads 88, 96 engaging the rod shoulders 104, 105 and disposing the rod in a central position, in which the cross-piece 74 is located approximately midway within the body and housing slots 75, 73, to allow the body 10 to be shifted longitudinally relative to the slip and drag block housing 46 and the upper and lower slips 13, 28.

Although the springs 85, 86 and valve heads 88, 96 are effective to center the control rod 77, in the manner described above, through engagement with the rod shoulders 104, 105, the latter are effective to engage the valve heads 88, 96 and hold them in open positions. Thus, a downward force imposed on the control rod 77 will cause the lower shoulder 105 to engage the lower head 96 and shift it off its seat 97 to open position. Similarly, an upwardly directed force imposed on the control rod 77 will shift the upper shoulder 104 into engagement with the upper valve head 88, to move it out of engage-

ment with its valve seat 89 against the force of the spring 85.

The springs 85, 86 are cooperable with their respective valve heads 88, 96 to shift the latter to valve closing position. However, the fluid pressure within the tool is effective to shift each valve head against the force of its associated spring to open position, during the actual elevating or lowering of the tool in the well casing, in the manner described hereinbelow.

The parts are so proportioned and arranged with respect to one another that during the lowering of the control rod 77 with respect to the body 10 the cross-piece 74 is not only placed in a position of engagement with the lower ends of the body slots 75 and housing slots 73, to prevent the slips 13, 28 from being expanded against the well casing, but the lower rod shoulder 105 engages the lower valve head 96 to move and hold it off its valve seat 97, thereby allowing fluid to flow upwardly through the valve cage 41 into the body 10, passing upwardly through the body passage 87 and around the rod 77, the pressure of the fluid bearing against the upper valve head 88 and shifting it to open position from its valve seat 89 against the force of the spring 85, this fluid then passing outwardly through the upper valve cage 27 for discharge into the well casing D above the packer A.

When the control rod 77 is moved in an upward direction, the upper shoulder 104 engages the upper valve head 88 to positively hold it off its seat 89. When this occurs, the lower shoulder 105 has been elevated considerably above the lower valve head 96. However, any fluid flowing relatively downwardly around the upper valve head 88 and into the body passage 87 will engage the lower valve head 96 and unseat it against the force of its spring 86, the fluid discharging through the lower valve cage 41 into the casing D below the well tool. When an external force is removed from the control rod 77, then, as stated above, the springs 85, 86 are effective to engage both of the valve heads 88, 96 with their seats 89, 97, and to shift the control rod 77 to the neutral position within the body and housing slots 75, 73, thereby preventing passage of fluid in both directions through the body 10 of the well packer.

The control rod 77 is shifted downward or upward with respect to the body 10 of the tool because of the frictional resistance offered by the packing cups 22, 36 against the wall of the well casing. If such frictional resistance is insufficient, then it may be supplemented by a guide and drag spring 110, which is secured to the lower cage 41 by a retaining ring 111 attached to the cage by one or more screws 112, the spring 110 being bowed in an outward direction to frictionally engage the wall of the well casing D. The spring 110 and the upper and lower packing cups 22, 36 tend to resist longitudinal movement of the body 10 in the well casing, allowing the control rod 77 to be shifted in both an upward and a downward direction with respect to the body.

In the operation and use of the well packer bridge plug in a conduit string, such as a well casing, the tool A is inserted in the well casing D and a downward force is imposed on the control rod 77 to push the tool down the casing. Such downward force at first shifts the control rod 77 in a downward direction, to cause its lower shoulder 105 to unseat the lower valve head 96 and to locate the cross-piece or bar 74 in its lowermost position within the housing and body slots 73, 75, which locates the upper and lower slips 13, 28 in a neutral position with respect to the upper and lower expanders 17, 32. Downward movement of the control rod 77, acting through the cross-piece 74, then causes the rod 77, body 10 and slip and drag block housing 46 to move down as a unit through the well casing D, the slips 13, 28 remaining in their neutral position (Figs. 1 and 1a). During such downward movement, the fluid in the well casing can by-pass around the packing structures 22, 36 by flowing upwardly through the open lower valve seat 97

into the body 10, the fluid pushing the upper valve head 88 in an upward direction to open position against the force of the upper spring 85, and then passing out of the packer through openings in the upper valve cage 27.

The downward movement continues until the location in the well casing D is reached at which the tool A is to be anchored. During all of such downward movement, it is evident that the upper expander 17 is incapable of expanding the upper slips 13 against the well casing. When the setting location is reached, the downward force on the control rod 77 is released, the springs 85, 86 then shifting both the upper and lower valve heads 88, 96 to closed position, to close the body 10 against fluid passage in either direction, the lower valve head 96 engaging the control rod shoulder 105 to shift the cross-piece 74 to a neutral position.

Assuming that pressure is then imposed in the well casing D above the bridge plug A (see Figs. 2 and 2a), such pressure will then act down across the upper packing 22, as well as across the area of the body 10 and the upper valve head 88, shifting the body 10 and all parts connected thereto, which includes the upper expander 17, in a downward direction relative to the slips 13, 28, which do not move downwardly because of the frictional resistance against the well casing afforded by the drag blocks 44. The upper expander 17 is then shifted within the upper slips 13 to expand the latter outwardly into anchoring engagement with the well casing. As explained above, the slip retainer and retractor ring 60 is shifted out of its holding position with respect to the slips 13 to allow them to move in an outward direction into anchoring engagement with the well casing. Thus, the packing 22 prevents fluid passage between the body 10 of the tool and the well casing D, the upper valve head 88 prevents downward passage of fluid through the valve body 10, and the upper expander 17 and upper slips 13 prevent downward movement of the entire tool A in the well casing D.

If a pressure differential is present below the well packer instead of above it, as has just been assumed, then the fluid under pressure will act in an upward direction on the lower packing 36, the body 10 of the tool and lower valve head 96, shifting the packing 36 and the body 10, as well as all parts connected thereto, including the lower expander 32, in an upward direction with respect to the drag housing 46 and the slips 13, 28 (see Fig. 3). The lower expander 32 will then be moved up within the lower slips 28 to shift the latter outwardly into anchoring engagement with the well casing. The first portion of the upward movement of the body 10 and lower expander 32 removes the lower slip retainer and drag ring 61 from their confining position around the lower slip shoulders 67, in order to allow the lower slips 28 to expand outwardly. Such upward movement of the body 10 also shifts the upper expander 17 out of wedging engagement with the upper slips 13, and causes the upper slip retainer and retractor ring 60 to engage the tapered surfaces 63 interconnecting the shoulders 62 and arms 53, to urge the slip heads 14 inwardly to their retracted position.

Thus, it is apparent that once the force on the control rod 77 has been removed the pressure in the well casing D itself is effective to prevent either downward or upward movement of the plug A therewithin, depending upon the direction in which this pressure is acting.

In the event it is desired to release the tool A and move it to a different location in the well casing D, or remove it entirely from the well casing, a suitable mechanism is provided which becomes coupled to the control rod 77, allowing the latter to be moved in an upward direction within and with respect to the packer body 10. The cross-piece 74 is thus moved upwardly into engagement with the upper ends 75b, 73b of the body and housing slots 75, 73 (Figs. 4 and 4a), which will effectively place the housing 46 and slips 13, 28 in a neutral

position between the upper and lower expanders 17, 32, and hold them in that position during upward movement of the control rod 77 within the casing D, which, of course, will also carry all of the parts upwardly in the well casing with it as a unit, since the cross-piece 74 effectively connects the control rod 77 to the body 10 and the housing 46. This position is disclosed in Fig. 4a. During such upward movement, the upper shoulder 104 engages the upper valve head 88 and holds it off its seat 89, the fluid being allowed to pass downwardly into the body 10 of the tool to unseat the lower valve head 96 against the force of its spring 86 for discharge through the openings in the lower valve cage 41. The tool A may then be elevated to a higher position in the well casing and the force on the control rod 77 again released, to allow the well packer to set itself in leakproof condition against the well casing. Of course, the tool could also be lowered in the well casing to another location, the downward force on the control rod 77 then being released to allow the well packer A to anchor itself in the well casing.

From the foregoing description, it is apparent that a well packer or bridge plug has been provided which is capable of being anchored in a well casing, or similar well conduit, against movement in both longitudinal directions, and which can be released for the purpose of being reset at either a higher or a lower position in the well casing, or to be removed entirely therefrom. The tool is simple in its operation and has a minimum of moving parts. The slips themselves are either retracted or expanded, the slips moving between retracted and expanded positions as a result of a rocking or swinging motion about their anchoring points to the drag block housing 46. That is to say, the slips do not move in comparatively straight-line fashion between retracted and expanded positions, but are rocked or pivoted between those positions.

The tool may be run in the well casings by any suitable mechanism and it may also be retrieved therefrom by any suitable mechanism, such as a releasing device or overshot. A particular form of releasing and running-in device B is shown in the drawings.

The releasable device B for running-in the bridge plug in the well casing and for retrieving it therefrom, specifically disclosed in the drawings, includes an outer housing or cylinder 120 threaded onto a sub 121 which is, in turn, threaded into a collar 122 secured on the lower end of the tubular string C. The cylinder 120 has a depending wash-over sleeve 123 secured to it to facilitate the location of the overshot or retrieving apparatus centrally with respect to the bridge plug A. The lower portion of the wash-over sleeve 123 can encompass the upper valve cage 27, and will tend to centralize the housing or cylinder 120 with respect to the control rod 77 to which the retrieving and running-in device B is actually to be associated.

The control rod 77 extends upwardly to a substantial extent above the upper valve cage 27, being provided with an upper head 124 extending outwardly from the reduced diameter portion 78 of the control head to form an outwardly directed shoulder 125 to be engaged by the inward nose portions 126 of latch members or latch means 127 carried by an annular piston 128 slidable in the cylinder 120, and also along a mandrel 129 threaded into the lower end of the tubular sub 121. The mandrel 129 actually defines an annular cylinder space 130 with the housing 120. Leakage along the inner and outer walls of the annular piston 128 is prevented by suitable side seal rings 131 in its inner and outer surfaces slidably engaging the wall of the cylinder 120 and the periphery of the mandrel 129.

The upper portion of the piston 128 is enlarged, to provide a stop shoulder 132 engageable with a companion stop shoulder 133 on the mandrel 129. The piston is normally urged in a downward direction by a helical compression spring 134 encompassing the mandrel 129, 75 with its lower portion engaging the piston 128 and its

upper portion the lower end of the sub 121. Any fluid that might be disposed in the annular cylinder 130 above the piston rings may be dispelled from the cylinder through one or more bleeder ports 135 provided through the upper portion of the outer housing or cylinder 120 and communicating with the annular cylinder space 130.

The latches or dogs 127, as stated above, are pivoted to the lower portion of the piston 128, as by providing outwardly extending hooks 136 on the latches received within an annular groove 137 in the lower portion of the piston. These dogs 127 extend downwardly from the piston along the lower portion of the mandrel, the mandrel having a tapered nose 138 engageable with the upper surfaces 139 of the latch noses 126 and tending to urge the latches 127 in an outward direction. The lower ends 140 of the latches are engageable with a downward and inwardly inclined surface 141 in the lower portion of the cylinder or housing 120, which tends to urge the noses 126 of the latches under the control rod shoulder 125. When the latches are disposed in a still lower position, their outer surfaces 142 are engaged with a downward and inwardly tapering surface 143 disposed below the surface 141 just mentioned, which securely holds the latches 127 under the control rod shoulder 125.

The wash-over apparatus B is not only useful in retrieving the plug A from the well casing, but it is also useful in moving the plug down the casing in the first instance. To accomplish this purpose, a spider 144 is secured to the upper portion of the control rod 77 below its latching shoulder 125. This spider includes an outward ribbed portion 145 adapted to engage the downwardly flaring inner surface 146 on the lower end of the housing and cylinder 120. The ribbed portion 145 is secured to a sleeve 147, which rests upon a split snap ring 148 contained within a peripheral groove 149 in the control rod 77, in order to prevent downward movement of the spider 144 and its sleeve along the control rod. The upper end 150 of the sleeve 147 is tapered in an upward and inward direction and is spaced a sufficient distance below the rod shoulder 125 to allow the latch noses 126 to move inwardly into complete engagement with the control rod shoulder 125.

During downward movement of the apparatus in the well casing, the lower flaring surface 146 of the housing or cylinder 120 is engaging the spider 144 on the control rod 77, the downward motion of the tubing C, collar 122, sub 121 and cylinder 120 being transmitted through the spider to the control rod 77, shifting the latter to its lowermost position within the body 10, in which the lower valve head 96 is held open and the cross-piece or bar 74 is disposed at the lower ends of the housing and body slots 75, 73, thereby precluding setting of the plug in the casing. During such lowering movement, it is immaterial whether or not the latches 127 are coupled to the control rod 77 by being engaged under the rod shoulder 125, since the downward movement can be transmitted between the overshot housing 120 and the control rod 77. As disclosed in Fig. 1, the latches 127 are in a position to engage the periphery of the spider sleeve 147 and will not engage under the shoulder. The spring 134 is urging the piston 128 in a downward direction, but the piston cannot move downwardly since the latch noses 126 engage the spider sleeve 147.

When it is desired to remove the overshot or retrieving tool B from the plug A, in order to allow the latter to anchor itself in the well casing, the tubing string C need merely be elevated, which will elevate the housing or cylinder 120 with respect to the control rod 77, thereby removing the downward force on the control rod and allowing it to assume its neutral position, such as disclosed in Fig. 4a. Should the force of the spring 134 be sufficient to shift the latch noses 126 under the shoulder 125, upon upward movement of the cylinder 120 and mandrel 129, the release can be effected simply by applying pressure to the fluid in the tubing string C, this pressure passing downwardly through the sub 121 and the

mandrel 129, and being throttled because of the narrow space or annular orifice provided between the spider sleeve 147 and the narrow portion of the passage through the cylinder 120. Such throttling action builds up sufficient back pressure under the piston 128 to shift it in an upward direction against the force of the spring 134, carrying the latches 127 upwardly and causing the latch noses 126 to engage the lower end 138 of the mandrel 129 and be shifted laterally outward to a position in which the noses are incapable of engaging the control rod shoulder 125 (Fig. 1).

The tubing string C may now be elevated, to completely remove the retrieving device or overshot B from the control rod 77. If desired, the entire tubing string C and retrieving device B can be removed from the well casing. If the tubing string includes a well packer of the retrievable type (not shown) above the retrieving device B, then this well packer can be suitably manipulated to set it in anchored position in the well casing, whereupon fluid pumped down the tubing string C and through the retrieving device B can pass outwardly through the lower end of the wash-over sleeve 123 for outward passage through casing perforations (not shown), or through other openings in the well casing D. After the retrieving device B has been completely released from the control rod 77, the pressure in the tubing string can be relieved, the spring 134 shifting the piston 128 down to its initial position, which will cause the latches 127 to engage the companion surfaces 141, 143 at the lower portion of the cylinder 120, to urge the latches in an inward direction.

As stated above, release of the restraint on the control rod 77 then allows it to be urged to the central position by the springs 85, 86 and both the upper and lower valves 88, 96 of the bridge plug to close, the upper or lower slips 13 or 28 of the plug then engaging the casing D, depending upon the presence of a pressure differential above the bridge plug or below the bridge plug.

In the event it is desired to release the bridge plug A from the well casing D and retrieve it, the tubing string C, with the retrieving device or overshot B secured to its lower end, is lowered in the well casing, the wash-over sleeve 123 passing over the control rod 77, the upper tapered head 124 on the control rod engaging the latches 127, urging the latter in an upward and outward direction against the force of the spring 134 until the latch noses 126 are disposed lower than the latch shoulder 125 on the control rod. When the latches are so disposed, the spring 134 is again effective to shift the piston 128 downward, the lower portions of the latches engaging the tapered surfaces 141, 143 on the cylinder 120 to be urged inwardly under the control rod shoulder 125, the latches being shifted within the holding surface 143 of the cylinder, which will then secure the noses 126 under the shoulder 125.

Upward movement of the tubing string C then is communicated to the cylinder 120, and through the latches 127 to the control rod shoulder 125, shifting the control rod 77 in an upward direction, to cause its upper shoulder 104 to engage the upper valve head 88 and shift it upwardly to open position, as well as elevating the cross-piece 74 with respect to the body 10 of the packer and of the slip and drag block housing 46 to place it against the upper ends of the body and housing slots 75, 73, which locates the slips 13, 28 in a neutral position. The entire bridge plug A can now be elevated in the well casing to a new location, or it may be completely raised to the top of the hole and removed from the well casing, the fluid passing down through the open upper valve seat 89 into the packer body 10, unseating the lower valve head 96 against the force of its spring 86 for discharge into the casing D below the packer A.

The inventors claim:

1. In apparatus for retrieving a device from a well bore: a member adapted to be connected to a running-in

thereon engaged by said latch means when moved in said one direction to shift said latch means laterally in one direction toward a position to be coupled to the device; means for directing fluid under pressure from the tubular string to said piston to move said piston and latch means longitudinally of said cylinder members in the opposite direction to allow said latch means to shift laterally in the opposite direction to a position uncoupled from the device; and means on said other member engageable with said latch means to shift said latch means laterally in said opposite direction.

10. In apparatus for retrieving a device from a well bore: supporting means adapted to be connected to a tubular string to be lowered in a well bore adjacent the device; hydraulically operable means slideable along said supporting means; latch means connected to said hydraulically operable means and adapted to be coupled to the device; means engaging said hydraulically operable means for moving said hydraulically operable means and latch means longitudinally of said supporting means in one direction; said supporting means having a surface thereon engaged by said latch means when moved in said one direction to shift said latch means laterally in one direction toward a position to be coupled to the device; and means for directing fluid under pressure from the tubular string to said hydraulically operable means to move said hydraulically operable means and latch means longitudinally of said supporting means in the opposite direction to allow said latch means to shift laterally in the opposite direction to a position uncoupled from the device.

11. In apparatus for retrieving a device from a well bore: supporting means adapted to be connected to a tubular string to be lowered in a well bore adjacent the device; hydraulically operable means slideable along said supporting means; latch means connected to said hydraulically operable means and adapted to be coupled to the device; means engaging said hydraulically operable means for moving said hydraulically operable means and latch means longitudinally of said supporting means in one direction; said supporting means having a surface thereon engaged by said latch means when moved in said one direction to shift said latch means laterally in one direction toward a position to be coupled to the device; and means for directing fluid under pressure from the tubular string to said hydraulically operable means to move said hydraulically operable means and latch means longitudinally of said supporting means in the opposite direction to allow said latch means to shift laterally in the opposite direction to a position uncoupled from the device; and means on said supporting means engageable with said latch means to shift said latch means laterally in said opposite direction.

12. In apparatus for retrieving a device from a well bore: inner and outer cylinder members spaced laterally from each other to form an annular cylinder space and adapted to be coupled to a tubular string to be lowered in a well bore adjacent the device; a piston slideable in said annular cylinder space; latch means connected to said piston and adapted to be coupled to the device; means engaging said piston for moving said piston and latch means downwardly of said cylinder members; said outer member having a surface thereon inclined in a downward and inward direction and engaged by said latch means when moved downwardly of said cylinder members to shift said latch means laterally inward toward a position to be coupled to the device; and means for directing fluid under pressure from the tubular string to said piston to move said piston and latch means upwardly of said cylinder members to allow said latch means to shift laterally outward of the device to a position uncoupled from the device.

13. In apparatus for retrieving a device from a well bore: inner and outer cylinder members spaced laterally from each other to form an annular cylinder space and

adapted to be coupled to a tubular string to be lowered in a well bore adjacent the device; a piston slideable in said annular cylinder space; latch means connected to said piston and adapted to be coupled to the device; means engaging said piston for moving said piston and latch means downwardly of said cylinder members; said outer member having a first surface thereon inclined in a downward and inward direction and engaged by said latch means when moved downwardly of said cylinder members to shift said latch means laterally inward toward a position to be coupled to the device; said outer member having a second surface thereon inclined in a downward and inward direction engaged by said latch means to hold said latch means coupled to the device; and means for directing fluid under pressure from the tubular string to said piston to move said piston and latch means upwardly of said cylinder members to allow said latch means to shift laterally outward of the device to a position uncoupled from the device.

14. In combination: a device adapted to be disposed in a well bore and having an upper head provided with a surface converging in an upward and inward direction and a downwardly facing shoulder below said surface; a member adapted to be connected to a running-in string to be lowered in the well bore and to be disposed over the device; latch means carried by said member and adapted to engage said tapered head surface to be urged laterally outward of said head and to be disposed under said shoulder in engagement therewith to be coupled to the device; means for moving said latch means longitudinally of said member in one direction; said member having a surface thereon engaged by said latch means when moved in said one direction to shift said latch means laterally inward toward a position under said shoulder whereby said latch means engages said shoulder when moved upwardly with respect thereto; and means for moving said latch means longitudinally of said member in the opposite direction to allow said latch means to shift laterally outward out of engagement with said shoulder to a position uncoupled from the device.

15. In combination: a device adapted to be disposed in a well bore and having a head provided with an upwardly converging surface and a shoulder below said surface; inner and outer cylinder members spaced laterally from each other to form an annular cylinder space and adapted to be coupled to a tubular string to be lowered in a well bore adjacent the device; a piston slideable in said annular cylinder space; latch means connected to said piston and adapted to engage said tapered head surface to be urged laterally outward of the head and to be disposed under said shoulder to engage said shoulder and thereby to be coupled to the device; means engaging said piston for moving said piston and latch means downwardly of said cylinder members; said outer member having a surface inclined in a downward and inward direction engaged by said latch means when moved downwardly of said cylinder members to shift said latch means laterally inward toward a position under said shoulder to engage said shoulder and be coupled to the device; and means for directing fluid under pressure from the tubular string to said piston to move said piston and latch means upwardly of said cylinder members to allow said latch means to shift laterally outward of the shoulder to a position uncoupled from the shoulder and device.

16. In combination: a device adapted to be disposed in a well bore and having a head provided with an upwardly converging surface and a shoulder below said surface; inner and outer cylinder members spaced laterally from each other to form an annular cylinder space and adapted to be coupled to a tubular string to be lowered in a well bore adjacent the device; a piston slideable in said annular cylinder space; latch means connected to said piston and adapted to engage said tapered head surface to be urged laterally outward of the head and to be disposed under said shoulder to engage said shoul-

der and thereby to be coupled to the device; means engaging said piston for moving said piston and latch means downwardly of said cylinder members; said outer member having a surface inclined in a downward and inward direction engaged by said latch means when moved downwardly of said cylinder members to shift said latch means laterally inward toward a position under said shoulder to engage said shoulder and be coupled to the device; means for directing fluid under pressure from the tubular string to said piston to move said piston and latch means upwardly of said cylinder members to allow said latch means to shift laterally outward of the shoulder to a position uncoupled from the shoulder and device; and coengaging means on said outer member and device to transmit downward movement of said outer member to 15 said device.

17. In apparatus for retrieving a device from a well bore: a member adapted to be connected to a running-in string to be lowered in the well bore and to be disposed over the device; latch means carried by said member 20

and adapted to be coupled to the device; means for moving said latch means downwardly of said member; said member having a surface thereon engaged by said latch means when moved downwardly of said member to shift said latch means laterally inward toward a position to be coupled to the device; means for moving said latch means upwardly of said member to allow said latch means to shift laterally outward of the device to a position uncoupled from the device; and means on said member below said latch means engageable with the device to force the device downwardly in the well bore.
